CLAIM

The ornamental design for a spray dispenser head for container as shown and described.

DESCRIPTION

FIG. 1 is a front upper isometric view of a spray dispenser head for container showing our new design;

FIG. 2 is a rear upper isometric view thereof;

FIG. 3 is right side view thereof;

FIG. 4 is a left side view thereof;

FIG. 5 is a top view thereof;

FIG. 6 is a bottom view thereof;

FIG. 7 is a front view thereof;

FIG. 8 is a rear view thereof;

FIG. 9 is a front upper isometric view thereof, shown in use with an exemplary container;

FIG. 10 is a rear upper isometric view thereof;

FIG. 11 is right side view thereof;

FIG. 12 is a left side view thereof;

FIG. 13 is a top view thereof;

FIG. 14 is a bottom view thereof;

FIG. 15 is a front view thereof; and,

FIG. 16 is a rear view thereof.

The broken lines are shown for the purpose of illustrating both parts of the article as well as environmental subject matter of an exemplary container. None of the broken lines form part of the claimed design.

1 Claim, 8 Drawing Sheets
